UNITED STATES PATENT OFFICE.

WALTER CASWELL, OF NAPOLEON, MISSOURI.

VEHICLE-AXLE.

SPECIFICATION forming part of Letters Patent No. 275,994, dated April 17, 1883.

Application filed December 26, 1882. (No model.)

To all whom it may concern:

Be it known that I, WALTER CASWELL, of Napoleon, in the county of La Fayette and State of Missouri, have invented a new and useful Improvement in Vehicle-Axles, of which the following is a full, clear, and exact description, reference being had to the annexed drawings, forming part of this specification.

This invention relates to solid metallic axles for vehicles; and the invention consists of the novel construction hereinafter described and claimed.

In the drawings, Figure 1 is a side elevation of the axle, and Fig. 2 is a plan view of the same, partly in section.

The axle A, which is preferably to be made of steel, is constructed with a double T-shaped body, B, to secure the greatest strength with

the greatest economy of material. The central or connecting web, C, is made slightly wider at D than throughout its length on account of the perforations E for the bolts by which the hounds and bolster are to be secured to the axle.

I do not broadly claim a cast-metal axle. 25
What I claim is—

A straight cast-metal axle having the body B formed with a narrow central web, C, which is made with wider portions at D for the perforations E, substantially as shown and described. 30

WALTER CASWELL.
